UNITED STATES PATENT OFFICE.

WALTER F. HEEREN, OF PITTSBURGH, PENNSYLVANIA, ASSIGNOR TO HEEREN BROTHERS COMPANY, OF PITTSBURGH, PENNSYLVANIA, A CORPORATION OF PENNSYLVANIA.

DESIGN FOR A PENDANT.

Application filed March 30, 1922. Serial No. 1,449. Term of patent 3½ years.

To all whom it may concern:

Be it known that I, WALTER F. HEEREN, a citizen of the United States, residing at Pittsburgh, in the county of Allegheny and State of Pennsylvania, have invented a new, original, and ornamental Design for a Pendant, of which the following is a specification, reference being had to the accompanying drawing, forming part thereof.

Fig. 1 is a front view of a pendant, showing my new design;

Fig. 2 is a rear elevation; and Fig. 3, an edge elevation thereof.

I claim:

The ornamental design for a pendant, as shown.

WALTER F. HEEREN.
